TOY SANTA CLAUS FIGURE

Willard F. Miner, 410 N. Highway 59, Barrington, Ill.

Filed July 6, 1964, Ser. No. 80,706

Term of patent 14 years

(Cl. D34—4)

I claim:

The ornamental design for a toy Santa Claus figure, as shown.
